CLAIM

The ornamental design for a chain for slide fastener, as shown and described.

DESCRIPTION

FIG. 1 is a front perspective view of a chain for slide fastener.

FIG. 2 is a front view of the chain for slide fastener of FIG. 1.

FIG. 3 is a rear view of the chain for slide fastener of FIG. 1.

FIG. 4 is a left side view of the chain for slide fastener of FIG. 1.

FIG. 5 is a right side view of the chain for slide fastener of FIG. 1.

FIG. 6 is a cross-sectional view taken along a line 6-6 in FIG. 2 of the chain for slide fastener of FIG. 1; and, FIG. 7 is a cross-sectional view taken along a line 7-7 in FIG. 2 of the chain for slide fastener of FIG. 1.

The dot dashed lines which define the bounds of the claimed design form no part of the claimed design.

1 Claim, 7 Drawing Sheets
